PLUGGING CONTROL FOR ELECTRIC MOTORS

Prescott D. Crout, Schenectady, N. Y., assignor to Cutler-Hammer, Inc., Milwaukee, Wis., a corporation of Delaware

Application August 20, 1930, Serial No. 476,504

3 Claims. (Cl. 172—179)

The present invention relates to control of electric and other motors by plugging and has for its object to provide improved means for stopping a motor and terminating the power supply when it has come substantially to a standstill and before it begins to rotate in a reverse direction.

The accompanying drawing illustrates two systems embodying the invention.

10 Figure 1 shows the invention applied to an alternating current motor, wherein the motor is disconnected from the line when the speed of its shaft approaches zero value, while

15 Fig. 2 shows the invention as applied to a slip-ring type motor, whereby the motor is disconnected when the frequency in the rotor of the motor approaches that obtaining at standstill.

Referring to Fig. 1, a relay 1 has a magnet frame 2 equipped with shunting pole pieces 3.

20 Wound on one side of the magnet frame is a coil 4 which is connected in series with a second coil 5. The coil 5, together with a third coil 6, is mounted on an armature 7 of the electromagnet. This armature is pivotally supported on the side of

25 the magnet frame 2 opposite to that on which coil 4 is wound and it carries at its upper end a movable contact 8a, which is adapted to engage stationary contacts 8b at either side of the armature. A three phase motor 9 has connected to its

30 driving shaft a rotating brush 10, which engages intermittently stationary contacts 11 whenever the motor revolves. The brush 10 completes intermittently a circuit when passing over the stationary segments 11. An electromagnetic switch

35 12 having a winding 12a and normally open contacts 12b and 12c serves to connect the motor to the lines L¹ and L² for normal operation, while a second electromagnetic switch 13 having a magnet coil 13a and normally open contacts 13b, 13c,

40 serves to connect the motor to the lines for plugging. Switch 13 has in addition normally open auxiliary contacts 13d and 13e. The circuits of the magnet switches are controlled by a double throw switch 14 having stationary contacts 14a

45 and 14b and a movable contact or a knife blade 14c. There is also provided a relay 15 having a magnetic winding 15a, normally closed contacts 15b and normally open contacts 15c.

Referring more particularly to relay 1, the 50 coils 4, 5 and 6 should be designed so that their reactance is small relative to their resistance in order that the current flowing in the coils is substantially in phase with their terminal voltage. It will be understood that the coil 4 produces a 55 flux, part of which passes entirely through the

iron of the frame 2, while another portion thereof passes through the shunt poles 3 and thus affects the armature 7. On the other hand, the coils 5 and 6 produce fluxes which, after passing through the armature 7, bridge the air gap between the latter and the pole pieces and then travel through the pole pieces and through the iron frame. If the fluxes produced by the coils 4, 5 and 6 are substantially in phase with each other, they will exert a pull on the armature 7, 65 which is normally biased to the center position, in one direction or the other, depending upon the relative polarity of the coils 4, 5 and 6 respectively. The coil 5 is normally wound with a relatively small number of turns, while the coil 6 is wound 70 with a larger number of turns, so that with the coil 5 energized, the pull due to the action of coils 4 and 5 upon the armature is in a given direction, whereas with the coil 6 energized the flux initially induced in the center pole, by the coil 5, is reversed so that the resultant pull on the armature is opposite to the first direction. Thus, by alternately opening and closing the circuit of the coil 6, the pull on the armature may be periodically 75 reversed, the frequency of reversal depending 80 upon the frequency of the interruptions. This characteristic of the relay is made use of in the present invention as will be more fully explained later.

The controller operates in the following manner:

The lines L¹, L² and L³ furnish 3 phase alternating current, the line L³ being directly connected to one terminal of the motor. When it is desired to operate the motor under normal conditions, the switch blade 14c is moved to complete circuit with the lower contact 14a. This connects coil 12a of switch 12 across lines L¹ and L³, thereby closing the contacts 12b and 12c and completing the connection of the motor to the lines L¹ 95 and L². The motor therefore starts and comes up to speed in the usual manner. If it is now desired to stop the motor by plugging, the switch 14 is moved upward, completing circuit with the stationary contacts 14b. This deenergizes the 100 switch 12, thus disconnecting the motor from lines L¹ and L². At the same time, circuit is completed from L¹, through coil 13a, normally closed contacts 15b of relay 15 and contacts 14b and 14c to line L³. Thus the switch 13 is energized, 105 thereby closing its contacts and reconnecting the motor 9 to the lines L¹ and L² but in the reverse direction. The motor thereupon acts as a generator, supplying power back to the line and thus slows down.

When switch 13 closes, circuit is also completed from the line L^1 , through the contacts 13e, coils 4 and 5, and contacts 13d, to line L^3 . The relay is therefore energized and its armature tends to move to close the circuit between contact 8a and one of the contacts 8b. An intermittent circuit is also completed from line L^1 over brush 10, stationary contacts 11, coil 6, contacts 13d to line L^3 . The coil 6 is thus also energized but intermittent. 10 At a frequency depending upon the speed of the motor and thus the armature 7, due to the reversal of the pull described heretofore, tends to oscillate from one side to the other. As long as the speed of the motor, and thus the frequency 15 of the interruptions of the circuit from coil 6, is high, the amplitude of the vibration of the armature 7 is not sufficient to cause the contacts 8a to engage the contacts 8b. As the motor slows down, however, the frequency of interruptions of the 20 circuits of the coil 6 decreases, and thus the frequency of the oscillations of the armature also decreases, until ultimately the motor approaches standstill. The frequency of the reversals of the 25 armature is then sufficiently low, so that its amplitude increases to complete circuit between the contacts 8a and one or the other stationary contacts 8b. This completes a circuit from line L^1 through contacts 8a and 8b through coil 15a, contacts 14b and 14c to line L^3 , thus energizing relay 30 15 and opening normally closed contacts 15b and closing normally open contacts 15c. The opening of contacts 15b de-energizes the switch 13 and thus disconnects the motor from the line, while the closing of contacts 15c maintains the circuit 35 of the coil 15a independently of the contacts 8a and 8b. The relay 15 thus remains energized and prevents the switch 13 from reclosing until switch 14 is opened, which restores the equipment to the initial starting position. 40 The system shown in Fig. 2 employs a relay similar to that employed in the system of Fig. 1 but the relay is represented only by its coils 20 and 21 corresponding respectively to the coils 4 and 5 of Fig. 1 and its contacts 36 corresponding to 45 contacts 8a in Fig. 1. An induction motor 22 of the slipring type has primary terminals 23, 24 and 25 and secondary terminals 26, 27 and 28, the latter being connected through a 3 phase variable resistance 29. A double throw reversing switch 50 30 is connected to the lines L^1 and L^2 and its center poles are connected to the normally closed contacts 33 and 34 of a magnet switch 31, having a winding 32 and a normally open contact 35. The coil 20 of the relay is connected to the primary 55 terminals 23 and 24 of the motor, while the coil 21 is connected to the secondary terminals 27 and 28. It will be observed that when the motor runs at full speed, the frequency in the secondary circuit of the motor and therefore in the coil 21 is 60 very low, so that the difference in frequency in the two coils of the relay is very great. Thus the direction of the pull on the armature of the relay varies rapidly and the armature cannot oscillate far enough to close the contacts 36. However, as 65 the motor approaches standstill the frequency in its secondary circuit and hence the frequency in the coil 21 approaches that of the coil 20, so that

the frequency of oscillations of armature of the relay is a minimum and it is capable of closing the contacts 36.

The device operates as follows:

Assume that the reversing switch 30 is thrown upward and the motor runs at full speed in a given direction. If it is now desired to stop the motor by supplying reverse power thereto or plugging it, the reversing switch is thrown in the downward direction, thereby reversing the connection between the lines L^1 and L^2 and the terminals 23 and 24 respectively. Reversal of the power causes the motor to slow down and to approach standstill. When the motor approaches zero speed, the frequency in the coil 21 approaches that of the coil 20 and the relay closes the contacts 36 in the aforescribed manner, thereby energizing coil 32 of the switch 31 and opening normally closed contacts 33 and 34 thus disconnecting motor terminals 23 and 24 from the line and terminating power supply to the motor. At the same time the normally open contact 35 closes, thus maintaining switch 31 energized independently of the contacts 36 and preventing re-establishment of power supply to the motor until reversing switch 30 is opened when switch 31 is again de-energized and normal conditions are restored.

It is to be understood that this invention is not limited to the specific type of relay shown in the drawing, as it is obvious that any type of relay which responds to the difference of two frequencies in the manner described may be employed.

Also, the constant reference frequency as well as the variable frequency which responds to the motor speed may be generated in any other well known manner than that described.

What I claim as new and desire to secure by Letters Patent is:

1. In a system for stopping electric motors, in combination, plugging means and automatic control means to limit duration of action of the former means, said automatic means comprising a relay having an armature and means to produce a unidirectional torque upon said armature and further means to reverse said torque with a frequency variable with the motor speed.

2. In combination a motor, a control relay therefor, having an armature, means to produce a unidirectional torque upon said armature and means to reverse said torque with a frequency which is a function of the motor speed.

3. In a system for stopping a motor by plugging, in combination, a switch for reversing the power supply to said motor, and a relay for controlling said switch upon reverse power connection, said relay having an armature, a coil energized from an alternating current source of a given frequency and producing a torque upon said armature and a second coil energized at a frequency variable with the motor speed and causing said torque to reverse at a frequency which is a function of the motor speed.

PRESCOTT D. CROUT.
